J. C. GENTRY.

Grain Mill.

Patented Mar. 18, 1836.

Joseph Gentry of Dayton Ohio
Letters Patent

The Schedule referred to in these Letters Patent and making part of the same containing a description in the words of the said Joseph Gentry himself of his Improvement in the metallic Mill, for grinding Grains and other substances.

To all to whom these presents shall come: Be it known that Joseph Gentry of Dayton in the County of Montgomery and State of Ohio, have invented a new and useful structure which I denominate "Gentry's Metallic Mill" for Grinding all kinds of grain, and other materials usually ground upon Mills, and which I describe as follows: Viz. The "Gentry Metallic Mill" is constituted of one metal cylinder of any dimensions, the body of the cylinder to be composed of cast iron, and plated or banded externally with cast steel, or any other suitable metal, and turned to a true surface; and a metallic concave, (with steel plates inserted), with a smooth interior surface, being of the same length of the cylinder, and nearly of the same curve, and so formed as that the interior surface shall nearly correspond to half the circumference of the exterior surface of the cylinder, ranging from such corresponding circles only, from a point to commence about half way, from the lower edge of the when placed horizontally against the cylinder; and the variation from that point up to be such as to admit the various kinds of grain to be introduced below; whilst the other portions of the concave are near enough to the cylinder to gradually reduce the grain to flour or meal. This cylinder and concave are to perform the operation of grinding, the concave being principally placed in a frame of wood or iron, and the cylinder to be connected with it as to turn with it, the concave being placed in such relation to the cylinder that the person turning the mill, may by turning same at its top and bottom, set the mill to grind when or finer as he may desire. A hopper and shoe are to be placed above, to hold and introduce the grain &c. The interior surface

if the concave is to be so cast as to receive the cast steel or other metallic ribs, at small intervals. These ribs being formed in the manner of a door-latch, to be driven into the groove, left in the castings, and made to project their surfaces, about one sixteenth of an inch beyond the smooth surface of the concave. The smooth surfaces, both of the ribs in the concave and the cylinder, are to be picked by a cast steel pick so as to produce serrated surfaces, to each other. For the purpose of avoiding any injury which these surfaces, might sustain from any foreign substance which might accidentally be introduced into the mill. A stiff spring is placed at each bar in which the cylinder moves, these springs will yield to any resistance offered by substances of the kind referred to, and will enable them to pass through the mill without of feeling an injury. At either or both ends of the shaft which passes through the cylinder there is a pulley to attach the mill to the driving power. What I claim as my invention, discovery, or improvement in the above machine, is the steel or other metallic ribs, in the manner of fixing them in the concave, and the cast steel or other suitable metal plated, or painted on the cast cylinders. The manner of reducing the action of the cylinder by springs, back of the bars, on which the journals rest. The manner of picking the cylinder on its presenting the sharp edges to each other as described above.
